(57) **CLAIM**

The ornamental design for a bottle lid as shown and described.

DESCRIPTION

FIG. 1 is a top perspective view of a bottle lid showing my new design;

FIG. 2 is a bottom perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is rear elevational view thereof; and,

FIG. 9 is a top perspective view thereof, with the mouthpiece in an alternative position.

The broken lines illustrate portions of the bottle lid which form no part of the claimed design.

1 Claim, 9 Drawing Sheets
